PEN

Pietro Gulizia, Chicago, Ill.

Application June 13, 1935, Serial No. 26,339

4 Claims. (Cl. 120—47)

This invention relates generally to pens, and more particularly to a novel and improved pen of the fountain type.

The present invention relates to a pen structure as disclosed in a patent issued to me on January 1, 1935, bearing No. 1,986,394, and includes some additional improvements in said structure, which improvements should greatly enhance the practicability and usefulness of the pen.

10 An object of the present invention is to provide in a pen of the character described novel and improved means for permitting the escape of air which collects in the barrel above the piston.

Another object of this invention resides in 15 novel and improved means for closing said air escape openings during use of the pen, said closing means being in the form of a cap which will conceal and house the operating mechanism employed for filling the pen.

20 A further object of the invention is to provide in a pen of the character described novel and improved means for positively limiting movement of the reciprocating plunger in both of its extreme end positions.

25 A still further object of this invention is to provide a pen of the character described which will be simple in construction comprising only a few parts which may be readily assembled in operative position and which may be produced along 30 lines for low cost manufacture, while at the same time being highly efficient for carrying out the purposes for which it is designed.

With the foregoing and other objects in view which will appear as the description proceeds, 35 the invention consists in certain novel features of construction, arrangement and combination of parts hereinafter fully described, illustrated in the accompanying drawing, and particularly pointed out in the appended claims, it being understood that various changes in the form, proportion, size and minor details of the structure may be made without departing from the spirit or sacrificing any of the advantages of the invention.

40 For the purpose of facilitating an understanding of my invention, I have illustrated in the accompanying drawing, a preferred embodiment thereof, from an inspection of which when considered in connection with the following description, my invention, its mode of construction, assembly and operation, and many of its advantages should be readily understood and appreciated.

45 Referring to the drawing in which the same characters of reference are employed to indicate corresponding or similar parts throughout the several figures of the drawing:

Figure 1 is a longitudinal sectional view through a pen embodying my invention;

50 Fig. 2 is a plan view taken on line 2—2 of Fig. 1;

Fig. 3 is a transverse sectional view taken on line 3—3 of Fig. 1;

Fig. 4 is a transverse sectional view taken on line 4—4 of Fig. 1;

Fig. 5 is a transverse sectional view taken on 5 line 5—5 of Fig. 1;

Fig. 6 is a transverse sectional view taken on line 6—6 of Fig. 1; and

Fig. 7 is a transverse sectional view taken on 10 line 7—7 of Fig. 1.

Referring to the drawing more specifically by characters of reference, the numeral 10 designates generally a barrel, the hollow interior of which provides an ink reservoir 11. This reservoir is cylindrical in shape and is adapted for receiving and holding a supply of ink or other writing fluid and has disposed therein a plunger or piston which is adapted for reciprocatory movement therein.

The lower end of the barrel 10 is internally 20 threaded, as shown at 12, within which is threaded a pen section 13 within which is adapted to be disposed my improved feeder, generally designated by the reference character 14, the construction of which is to be presently more fully described.

The pen section 13 is provided intermediate its ends with an annular shoulder 15 upon which is adapted to be disposed a suitable washer 16 made of any suitable resilient material and against 30 which the lowermost edge of the barrel 10 is adapted to press to thereby securely seal the joint between the barrel and the end section against the escape of ink.

Disposed within the barrel 10 is a helical or 35 screw member 17 which is provided with a relatively steep pitch, said member being provided with a reduced portion 18 at one end thereof, which reduced portion is adapted to be received in a central opening 19 provided in the pen section 40 13, whereby said member 17 will be swiveled within said opening 19, said opening forming a bearing for said member to permit rotary movement thereof. The member 17 extends centrally within said barrel 10 and is adapted for rotary movement therein, as will be hereinafter more fully explained.

The member 17 has mounted thereon a piston or plunger generally designated by the reference character 20, said plunger consisting of a 50 cylindrical member 21, the interior of which is hollow and may be filled with a resilient material 22 which will snugly encase the member 17 to prevent the passage of ink past the piston or plunger 20. In the end walls of the member 21 55 are provided suitable rectangular slots 23, as shown in Fig. 5, said slots being of a size and shape to permit the passage therethrough of the screw threads provided on the member 17.

The member 21 is provided with laterally ex- 60

- tending annular flanges 24 and 25 between which is disposed the piston ring 26 formed of resilient material such as cork, or the like. The laterally extending annular flanges 24 and 25 form opposed end abutments for the sleeve-like body or piston ring 26 which resist the tendency of said ring to increase in length due to rotary compression thereof when inserted in the cylinder or reservoir 11. By reason of this, and by reason of 10 the fact that the body of the piston ring 26 is made of resilient material, the piston will fit snugly within the cylinder and thereby seal the same to prevent the passage of ink past the piston while permitting of the reciprocation of the piston 15 within the pen barrel.
- Rigidly secured to the top and bottom end walls of the cylindrical member 21 are upstanding projections or teeth 27 and 28, respectively, for the purpose to be presently more fully described. Although in the embodiment illustrated there are shown two such projections or teeth for each of the end members, it is to be understood that only one of said projections may be sufficient for each of said end members. 20
- 25 In the upper end of the barrel 10 is rigidly and permanently secured a member 29, said member being provided on the outer periphery thereof with a pair of diametrically opposed longitudinal grooves 30, said grooves being provided in the enlarged lower portion of the member 29, said enlarged portion terminating in a shoulder 31, which shoulder is flush with the topmost edge of the barrel 10. The member 29 is provided also with an intermediate reduced portion 32 which is externally threaded for receiving in threaded relation the hollow cap 33, said hollow cap when in closed position, as shown in Fig. 1, will be effective for closing the passages 30 thereby preventing the escape of ink through the same should 30 any ink escape past the piston or plunger 20.
- The member 29 is provided adjacent its upper end with a still further reduced portion 34, as shown in Fig. 1, and said member 29 has its entire interior surface screw threaded for the purpose 35 of receiving therein in threaded relation the following mechanism.
- Disposed within the lower portion of the interior of the member 29 is a threaded nut 35 which is spaced from a similar nut 36 and between which is disposed a washer 37 of suitable resilient material. The said nuts 35 and 36 will form a bearing for the upper cylindrical end of the member 17 and the resilient washer 37 will form a further seal against the passage of ink should any 40 ink escape past the piston or plunger 20. Both of the washers 35 and 36 are provided on their upper faces with the transverse grooves 38, shown in dotted lines in Fig. 4, by means of which with the use of a proper tool, said washers may be assembled and disassembled with the member 29. 45
- The upper end of the member 17 projects beyond the nut 36, as shown in Fig. 1, said upper end being bifurcated, as shown at 39, and is adapted to receive between its bifurcations the rectangular head 40 of a member 41 upon which is loosely mounted for rotation a member 42, said member 42 being provided with a depending externally threaded reduced portion 43 which is threaded in the open upper end of the member 29. The member 41 extends beyond said member 42 and has its free end permanently secured to a hollow cap 44, said cap extending downwardly over the member 42 and the reduced portion 34

of the member 29 and is adapted for rotation relative to said members.

When in assembled position it will be readily noted that the rotation of this cap 44 will rotate the rectangular head 40 which in turn will impart rotary movement to the member 17. This cap, therefore, will form the operating mechanism for actuating the member 17 when it is desired to fill or empty the pen.

In order to facilitate the turning of the cap 10 member 44, the same may be provided with a knurled exterior surface, as shown at 45. The member 42 is provided with the depressions 46, shown in Fig. 1, which may be reached by a suitable tool through the openings 47 extending 15 through the top of the cap member 44 when it is desired to assemble or disassemble the member 42 from the member 29. The cap 33 which is threaded on the member 29 is of a size to completely enclose the cap 44, and when in the fully 20 closed position, as shown in Fig. 1, the cap 33 will, as already stated, completely close the openings 30 thereby preventing the escape of ink through said openings should any ink escape past the piston or plunger 20. The cap 33 is also of 25 such a size as to form a substantially continuous uninterrupted outer surface with the barrel 10 when in assembled position thereby adding to the attractive appearance of the pen.

As already stated, the screw member 17 is swivelly mounted at its lower end in the pen section 13, the reduced end 18 on said screw member providing an annular shoulder which takes the end thrusts imparted to the end member in one direction. The end thrust in the other direction 35 is taken by the threaded shank of the member 41.

In order to prevent movement of the plunger or piston 20 when it has reached the end of its stroke in either direction, I provide positive locking means which are in the form of cam surfaces provided on the bottom edge of the end section 29 for limiting the rotary movement of the plunger 20 in one direction and similar cam surfaces on the upper edge of the pen section 13 for limiting the rotary movement of said piston or plunger in the other direction. Thus in the embodiment illustrated, the lower edge of the member 29 is provided, as shown in Fig. 1, with the cam surfaces 48, which surfaces will engage the projections or teeth 27 when the piston is in its uppermost position, thereby locking the piston against further movement. Similarly the upper edge of the pen section 13 is provided with the cam surfaces 49 which will be engaged by the projections or teeth 28 when the piston has been moved to its lowermost position, thereby locking said piston against further rotary movement.

The provision of this locking means will be effective for definitely and positively calling the attention of the operator to the fact that the piston has reached the end of its stroke and that the screw actuating means should not be operated any further. Unless this means is provided, there is a possibility of the screw being turned to such an extent as to damage the piston. The means provided herein should be very effective for preventing such damage to the mechanism.

A further feature of this improved pen resides in the improved construction of feeder, which is generally designated by the reference character 14. In the embodiment illustrated, the feeder 14 has a central chamber 50, the upper end of which is in communication with the reservoir 11 by means of the openings 51 extending through 75

the top wall of the pen section 13. As shown in Fig. 1, the top of said chamber 50 is flared out at its outer edge, as shown at 52, so that the uppermost edge of said feeder will be relatively thin thereby preventing the obstruction of any of the passages 51 for the passage of ink into the chamber 50. The feeder 14 is provided with the longitudinally disposed groove 53 extending on the outside thereof, which groove is in communication with the central chamber 50 through a plurality of transverse openings 54. The pen point 55 is disposed around the feeder directly above the longitudinal groove 53 provided therein. This construction of feeder I have found permits a free flow of ink to the pen point and also prevents the clogging of the same.

To complete the pen structure I provide a suitable cap 56 which is threaded to the lower end of the barrel 10, said cap enclosing the feeder 14 when the latter is not in use.

When the pen is completely assembled, as shown in Fig. 1, and it is desired to fill the same, the cap 33 may be removed and the knurled cap 44 rotated to impart rotary movement to the screw member 17, which member is held against longitudinal movement. The rotary movement of the member 17 will in turn impart reciprocatory movement to the piston or plunger 20 causing the same to move up or down depending upon the direction of rotation.

When the pen is being filled, the upward movement of the piston 20 will force the air beyond the piston out through the passages 30, thereby preventing the formation of an air trap in the upper portion of the barrel of the pen. When the pen has been completely filled, the projections or teeth 27 on the plunger will engage the cam surfaces 48 thereby immediately indicating to the operator that the piston or plunger has reached the end of its upward stroke. Similarly when all of the ink has been expelled from the pen, the projection 28 will engage the cam surfaces 49 indicating to the operator the end of the downward stroke. When the pen has been completely filled, the cap 33 is again screwed into place, in which position it will completely close the air escape openings 30 at the same time concealing from view the screw operating cap 44.

The novel features of construction and the combination and arrangement of the parts of my improved pen result in an article having many practical commercial uses. It will be readily apparent that the structure may be quickly and economically manufactured, and by reason of the small number of parts may be readily assembled in a minimum of time by practically unskilled labor. The construction of the several parts is such that the same will be durable and will not readily get out of operative order in use. Furthermore, the several parts are so constructed and assembled within the barrel of the pen that the ink capacity of the same is materially increased over that of pens heretofore used, and particularly over that of pens of corresponding size employing the conventional compressible rubber sack.

It is believed that my invention, its mode of construction and assembly, and many of its advantages should be readily understood from the foregoing without further description, and it should also be manifest that while a preferred embodiment of the invention has been shown and described for illustrative purposes, the structural

details are nevertheless capable of wide variation within the purview of my invention as defined in the appended claims.

What I claim and desire to secure by Letters Patent of the United States is:

1. In a fountain pen of the character described, the combination of a barrel, a piston therein fixed against rotation but moving longitudinally, a spiral shaft passing through said piston, a plug in each end of said barrel, and means provided on the interior end of each of said plugs co-operating with means provided on said piston for positively limiting movement of said piston at the extreme ends of its stroke.

2. In a fountain pen of the character described, the combination of a barrel, a piston therein fixed against rotation but moving longitudinally, a spiral shaft passing through said piston, a plug disposed in each end of the barrel and forming bearings for the ends of said spiral shaft, cam surfaces provided on the interior face of each of said plugs, means provided on the piston at each end thereof for co-operation with said cam surfaces to positively lock said piston against rotary movement at both ends of its stroke.

3. In a fountain pen of the character described, the combination of a barrel, a piston mounted in said barrel and fixed against rotation but moving longitudinally, a spiral shaft passing through said piston, a plug forming a bearing for one end of said spiral shaft disposed in the upper end of said barrel, said plug having an enlarged lower portion adapted for engagement within the free upper end of said barrel, a longitudinal groove provided on the periphery of said enlarged position of said plug adapted for forming an outlet to the atmosphere from said barrel when the plug is in assembled position within said barrel, a reduced threaded portion provided on said plug immediately adjacent said enlarged lower portion, means carried by said plug for actuating said shaft, and a cap engaging the threaded reduced portion of said plug for enclosing the shaft actuating means and for closing the air outlet when said cap is in assembled position with said barrel.

4. In a fountain pen of the character described, the combination of a barrel, a piston therein fixed against rotation but moving longitudinally, a spiral shaft passing through said piston, a plug disposed in each end of said barrel forming a bearing for each end of said shaft, the plug disposed in the upper end of said barrel having an enlarged lower portion for engaging with the free end of said barrel, said enlarged portion having a pair of diametrically opposed longitudinal grooves arranged on the periphery thereof forming outlets to the atmosphere when said plug is in assembled position with said barrel, means carried by said upper plug for actuating said shaft, including a knurled cap free to rotate on said upper plug and having a driving connection with said spiral shaft, a reduced portion provided on said plug immediately adjacent the enlarged lower portion, and a cap for engaging said reduced threaded portion on said upper plug, said cap being adapted for enclosing said shaft actuating means and being effective when in assembled position for completely closing said air outlets.

PIETRO GULIZIA.
